M. GOLDEN

LOCK

Filed Nov. 3, 1922

UNITED STATES PATENT OFFICE.

MAX GOLDEN, OF NEW YORK, N. Y.

LOCK.

Application filed November 3, 1922. Serial No. 598,795.

To all whom it may concern:

Be it known that MAX GOLDEN, a citizen of the United States, residing at New York city, in the county of New York and State 5 of New York, has invented certain new and useful Improvements in Locks, of which the following is a specification.

This invention relates to locks. Among the objects of the invention is to provide a 10 practical lock of the character described which shall be durable and simple in construction, efficient in operation, and burglar-proof to a high degree.

Other objects of this invention will in part 15 be obvious and in part hereinafter pointed out.

The invention accordingly consists in the features of construction, combinations of elements and arrangement of parts which will 20 be exemplified in the construction herein-after described and of which the scope of application will be indicated in the following claims.

In the accompanying drawings, in which 25 is shown one of various possible illustrative embodiments of this invention,

Fig. 1 is a partial front elevation of a door and frame to which is secured a lock embodying my invention;

30 Fig. 2 is a cross-sectional view taken through the lock along line 2—2 of Fig. 1 and showing the lock in sectional side elevation;

Fig. 3 is a cross-sectional view cut along 35 line 3—3 of Fig. 2; and

Fig. 4 is a cross-sectional view cut along line 4—4 of Fig. 3.

Referring in detail to the drawings, the lock 10 embodying my invention there illustrated is shown applied to a door 11 and a door frame 12. 13 indicates a face plate or attaching member secured to the door in any suitable manner as by means of screws 14 on which are mounted 45 some of the parts of the lock mechanism. The lock mechanism is assembled in a recess 14^a cut out in the door and covered by said face plate as will be readily understood.

The keeper for the lock comprises a portion 50 fixed to the door frame and a portion movable with the door. The fixed or stationary portion of the keeper comprises a keeper plate 39 which is counter-sunk into the door frame and secured thereto in any 55 suitable manner as by means of the screws

40. Extending from this keeper plate 39 is a keeper block 41 adapted to enter into a space 42 between the keeper blocks 43, 44, secured or forming part of the face plate 13. These members 43, 44 form the movable 60 portion of the keeper. In the form shown in the drawings, the keeper block 41 is of dove-tail shape and dove-tails into the correspondingly shaped space or recess 42 between the keeper blocks 43, 44, the three 65 blocks 41, 43, and 44 combining with the door when closed to form a strong keeper for the lock bolt 15. The latter is adapted to engage with said blocks through openings 41', 43', 44' respectively, provided therein and 70 adapted to register with each other so as to form one continuous recess for receiving the lock bolt.

The lock mechanism is assembled in the recess 14^a formed in the door and comprises 75 a lock bolt 15 formed with a rack 16 adapted to be engaged by a toothed segment 17 for reciprocating the lock bolt. The segment 17 is mounted on a shaft 18 extending through the opening in the door and having mounted 80 on each end thereof the usual interior and exterior door knobs 19, 20 respectively. Disposed adjacent the upper end of the lock bolt is a catch member 21 adapted to be reciprocated in guides 22, 22' secured on the 85 interior or forming part of the casing. This catch member 21 is preferably U-shaped so as to provide a cross piece 23 adapted to rest in one position on the upper end of the lock bolt 15 so as to keep the bolt in locking position. Extending from said cross member 23 90 are the parallel leg members 24, 25 defining the U-shaped opening 26. As will be understood, when this catch member is moved into position with the U-shaped opening disposed 95 over the lock bolt, the latter is free to be reciprocated therethrough. A spring 27 secured to the casing as at 28 normally maintains the catch-member in locking position with the cross-member 23 disposed over the 100 lock bolt 15. Means is provided for releasing the lock bolt either from the interior or exterior of the door. To this end the leg member 24 adjacent the interior of the door is provided with a lug or extension 29 adapted 105 to be engaged by a finger member 30, extending from the shank 31 of a knob or button 32 operable from the interior. Likewise, extending from the other leg 25 is a lug member 33 adapted to be engaged by a finger 110

member 34 extending from a shank 35, adapted to be operated by the key inserted in the usual key barrel mechanism shown generally at 38. The shaft 18 has an opening 37 formed therein to permit the projection of the finger member therethrough.

The operation of the lock will now be clear. When the door is closed, the dovetail member 41 registers in the space 42 between the keeper blocks 43, 44. The knob 20 is then manipulated so as to operate the segment 17 thus moving the lock bolt into the continuous opening in the keeper blocks formed by the registry of openings 41', 43', and 44' with each other. (See Figs. 2 and 3.) When the lock bolt has been thus fully drawn into the keeper blocks, the catch member 21 will be urged by the spring 27 into the position shown in Figs. 2 and 3 with the cross member 23 resting on the top of the lock bolt and thus keeping it in locked position. If it is now desired to open the lock from either the interior or exterior of the door, the button member 32 or the finger member 34, as the case may be, is operated to slide the catch member in its guides 22 against the spring 27 until the U-shaped opening 26 is disposed over the lock bolt and then either the interior knob 19 or exterior knob 20 turned so as to operate the segment 17 and withdraw the lock bar. In the withdrawn position, the lock bolt abuts against the spring 45 which extends from the casing so as to keep the lock bar partially in registry with the keeper blocks. In this way, unless complete turning of the segment is had, the door will always be somewhat locked.

It will thus be seen that there is provided a device in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:—

1. A lock comprising a movable portion and a wedge-shaped keeper, said movable portion having a wedge-shaped opening for receiving said keeper, a lock bolt for retaining said portions in engagement, and means

for reciprocating said lock bolt in said keeper.

2. A lock comprising a movable portion and a wedge-shaped keeper, a slidable lock bolt for said keeper, means for reciprocating said lock bolt in said keeper, and means for maintaining said lock bolt in closed position with respect to said keeper.

3. A door lock comprising a movable portion and a wedge-shaped keeper, said movable portion having a wedge-shaped opening for receiving said keeper, said keeper and movable portions having corresponding vertical openings, and a lock bolt for retaining said portions in engagement, and means for reciprocating said lock bolt in the vertical openings.

4. A door lock comprising a casing, a keeper comprising a stationary member secured to the door frame and a movable portion carried within the casing, said keeper portions having corresponding vertical openings, a lock bolt adapted to be reciprocated in said keeper openings, and means for maintaining said lock bolt in closed position with respect to said keeper.

5. A lock comprising a casing, a toothed lock bolt within said casing, means for reciprocating said lock bolt, said means comprising a shaft operable by the door knob, a pinion mounted thereon adapted to engage with the teeth of said lock bolt, and means for maintaining said lock bolt in closed position, said means comprising a spring pressed reciprocatory member formed with spaced leg portions and a solid end portion, the latter being adapted to rest on the lock bolt and prevent the latter from being raised, and means for reciprocating said spring pressed member.

6. A lock comprising a casing, a toothed lock bolt within said casing, means for reciprocating said lock bolt, said means comprising a shaft operable by the door knob, a pinion mounted thereon adapted to engage with the teeth of said lock bolt, and means for maintaining said lock bolt in closed position, said means comprising a spring pressed reciprocatory member formed with spaced leg portions and a solid end portion, the latter being adapted to rest on the lock bolt and prevent the latter from being raised, and means for reciprocating said spring pressed member, said means comprising a lug member extending from the free end of one of said leg members, and an actuating member adapted to engage said lug member.

In testimony whereof I affix my signature.
MAX GOLDEN.
